UNITED STATES PATENT OFFICE.

WILLIAM SCHUTTLER, OF CHICAGO, ILLINOIS, ASSIGNOR TO AMERICAN ARCH COMPANY, OF NEW YORK, N. Y., A CORPORATION OF DELAWARE.

ARCH-BRICK.

1,372,320.

Specification of Letters Patent. Patented Mar. 22, 1921.

Application filed October 21, 1918. Serial No. 259,098.

To all whom it may concern:

Be it known that I, WILLIAM SCHUTTLER, a citizen of the United States, residing at Chicago, in the county of Cook and State of Illinois, have invented certain new and useful Improvements in Arch-Bricks, of which the following is a specification.

This invention relates to arch bricks such as are used, for example, in locomotive fire-boxes, and particularly to side or wing bricks.

One of the primary objects of my invention resides in the provision of an improved brick which will readily accommodate itself to variations in the inclination of the side sheets of the fire-box, and to other irregularities and still have a firm seat. This, together with such other objects that may hereinafter appear, or are incident to my invention, I have obtained by means of a construction which I have illustrated in preferred form in the accompanying drawings, wherein:

Figure 1 is a longitudinal section through a locomotive fire-box; Fig. 2 is a section taken on the line II--II of Fig. 1; Fig. 3 is a fragmentary transverse section through the fire-box on the line III--III of Fig. 1; Fig. 4 is a fragmentary plan view of a portion of the arch shown in Figs. 1, 2 and 3; Fig. 5 is a side view of my improved brick, drawn on an enlarged scale, showing the manner of its application; Fig. 6 is a view similar to that of Fig. 5, and illustrating a modification of my invention; and Fig. 7 is a perspective of the brick shown in Fig. 5.

Referring now to Figs. 1, 2 and 3, the fire-box comprises the usual flue sheet 7, crown sheet 8, back sheet 9, throat sheet 10, and side sheets 11. The usual rearwardly and upwardly extending circulation tubes 12 connect the front and rear water legs and are adapted to support the arch indicated as a whole at A.

The arch comprises three rows of center bricks 13 which may be of any suitable type, but which are preferably of the construction shown. As shown the center bricks 13 have their end portions on the lower face of the brick cut away to provide supporting surfaces 14 for engagement with the circulation tubes 12. Each brick on its upper face has its end portions cut away or offset, as indicated at 15, forming a rib 16.

The arch is completed by two rows of

wing bricks 17, such wing bricks being preferably wedge-shaped and having their inner or thicker ends cut away on the lower face of the brick to form a projection or rib 18, the end of which is rounded, as at 18', and 60 a shouldered portion 19. The lower face of the shoulder 19 is flattened as at 20, and the vertical face is rounded or curved as indicated at 21. The outer ends of the wing bricks are inclined, as indicated at 22. 65

The parts are so proportioned that when the wing bricks are assembled the shoulders 19 rest upon the top faces of the ribs 16 on the center bricks and the ribs 18 rest upon the top surfaces of the center bricks, with 70 the rounded surfaces 21 abutting the surfaces of the cut away portions of the center bricks. The outer ends of the wing bricks engage the side sheets 11.

From inspection of Fig. 3 it will be seen 75 that the side sheets incline inwardly and in addition converge toward the rear of the fire-box, which is a common construction of fire-box. By reason of the curved surface 21 and the rounded end 18', the wing bricks 80 readily accommodate themselves to the compound inclination of the side sheets, for the bricks can swing on a substantially vertical axis on the rounded surface 21 and on a substantially horizontal axis on the rounded 85 ends 18' thus making it possible for the outer ends of the wing bricks to take a firm seat against the side sheets and the inner ends to take a firm seat on the center bricks. I am thus enabled to use one size of wing 90 brick.

It will be obvious that the wing bricks will accommodate themselves to different inclinations of the side sheets such, for example, as illustrated in Figs. 4 and 5 in dotted 95 lines, and that they will also accommodate themselves to irregularities not only in the side sheets but in the spacing between the side sheets and the circulation tubes such, for example, as might result from curvature 100 in the circulation tubes or in the side sheets themselves.

It will be apparent that my improved wing or end brick is applicable for use in connection with other forms of center brick. 105 Thus, for example, the application of the wing brick to a center brick having a plain or straight upper face, as shown in Fig. 6.

I claim:

1. An end arch brick for boiler fire box 110

arch constructions provided on one end with a surface adapted to take against a side sheet and on the other end with a substantially vertically extending convex surface adapted to abut against the adjacent structure and to permit swinging of the brick on a substantially vertical axis.

2. An end arch brick for boiler fire box arch constructions provided on one end with a surface adapted to take against a side sheet and on the other end with a rib adapted to rest upon an adjacent element and with a substantially vertically extending convex surface adapted to abut against the adjacent structure to permit swinging of the brick on a substantially vertical axis.
3. An end arch brick for boiler fire box arch constructions provided on one end with a surface adapted to take against a side sheet and on the other end with a rib adapted to rest upon an adjacent element and with a substantially vertically extending convex surface adapted to abut against the adjacent structure to permit swinging of the brick on a substantially vertical axis.
4. A side or wing brick for locomotive fire box arches having at one end a supporting surface and a substantially vertically extending convex surface therébelow, the supporting surface being adapted to rest upon and to support the brick from the adjacent structure and the convex surface being adapted to abut against the adjacent structure and to permit the brick to swing on a substantially vertical axis.
5. In a locomotive fire box provided with circulation tubes and center bricks supported on said tubes, wing bricks, the outer ends of which take against the side sheets and the inner ends of which rest upon the center bricks, each of said inner ends being pro-

vided with a substantially vertically extending convex surface adapted to abut against the adjacent structure whereby the wing bricks may have swinging movement on a substantially vertical axis.

6. In a locomotive fire box provided with circulation tubes and center bricks supported on said tubes, wing bricks, the outer ends of which take against the side sheets and the inner ends of which have ribs adapted to rest upon the center bricks and substantially vertically extending convex surfaces below said ribs adapted to abut against the ends of the center bricks whereby the wing bricks may have swinging movement on a substantially vertical axis.

7. A brick for a boiler fire box arch construction, adapted to be supported at an end thereof upon adjacent brick structure and having at said end a substantially vertically extending convex surface adapted to abut against the adjacent brick structure whereby said brick may have swinging movement on a substantially vertical axis.

8. An end brick for boiler fire box arch constructions adapted to be supported between a portion of the fire box structure and the adjacent brick structure of the arch, said brick at one end being adapted to rest against the fire box structure and so constructed at said end as to maintain the brick in a fixed horizontal angular relation with respect to the fire box structure against which it rests, and said brick at the other end being provided with a substantially vertically disposed convex surface adapted to abut against the adjacent brick structure whereby said brick may assume different horizontal angular relations with respect to the adjacent brick structure.

In testimony whereof I hereunto sign my name.

WILLIAM SCHUTTLER.
